UNITED STATES PATENT OFFICE

WILLIAM J. CAMPBELL, OF INDIANAPOLIS, INDIANA, ASSIGNOR TO AMERICAN SLICING MACHINE COMPANY, OF CHICAGO, ILLINOIS, A CORPORATION OF NEW YORK

SLICING MACHINE

Application filed June 11, 1928. Serial No. 284,294.

My invention relates to a slicing machine of the type in which a rotary knife is employed and is particularly applicable to use with a motor driven rotary knife. One object of the invention is to provide a simple, efficient and easily operated slicing machine. Another object is to provide a machine in which a carriage or work supporting member is so formed and so shaped as to take 10 pieces of maximum size for slicing. Another object is the provision of means for positioning a round or rounded piece of meat at the desired point on the meat carriage and for preventing any tendency thereof to roll 15 out of place and away from the rear abutment of the carriage. Another object is the provision of an improved pusher plate.

Other objects will appear from time to time in the course of the specification and 20 claims.

I illustrate my invention more or less diagrammatically in the accompanying drawings, wherein—

Figure 1 is a front elevation of my device;

Figure 2 is a section along the line 2—2 of Figure 1;

Figure 3 is a top plan view with parts broken away; and

Figure 4 is a front view of a variant form.

Like parts are indicated by like symbols throughout the specification and drawings.

A generally indicates the base of the slicing machine having the supporting members 35 or yielding supporting pads A¹.

Mounted on the base is a motor generally indicated as B with the motor shaft B¹ upon which is any suitable pulley B² about which passes the belt B³.

C generally indicates a rotary knife mounted upon the knife shaft C¹. Associated with it is a pulley C² about which passes the belt B³. The details of knife, knife bearing and the like form of themselves no part of the 45 present invention and need not be described in detail.

Positioned forwardly of the knife is the guard plate D which is provided with an arcuate edge D¹ which penetrates the forward 50 recess C³ of the knife. It will be observed

that the knife axis, while lying in a horizontal plane, is tilted somewhat from perpendicularity to the guard plate D, in order to bring the cutting arc of the knife forwardly into or in front of the guard plate D. 55

Mounted on the base A in any suitable manner is a gauge plate E which terminates adjacent the knife in an arcuate edge E¹ conforming generally to the arc of the knife. The gauge plate E may be positioned in a variety of ways but I illustrate it as mounted upon a housing member E² which is movable along a diagonal axis upon the frame, being controlled in any suitable manner in response to rotation of the knob E³. It will be understood that at all positions of adjustment the gauge plate lies in planes generally parallel with the plane of the guard plate D. 60

Positioned on the base forwardly of gauge and guard plate is the inclined track G herein shown as of circular cross-section and mounted at its ends on the supports G¹ G¹. G² is a centering or guide track herein shown as positioned beneath the track G as of rectangular cross-section. Mounted for movement along said tracks is the meat carriage 65 generally indicated as H.

It includes a base portion H¹ in actual engagement with the track G and a depending portion H² in engagement with the guide track G². H³ indicates any suitable adjusting means whereby the carriage H may be centered upon or slightly rotated about the track G in order to adjust the position of the carriage in relation to the gauge and guard 70 plate. 80

Mounted upon the top of the carriage is a plane surfaced plate H⁴ which terminates at the side normally farthest from the knife in an upwardly turned flange H⁵ generally perpendicular to the portion H⁴. H⁶ generally indicates a lateral extension from the carriage upon which is mounted a pusher plate guide pin H⁷ and a second pusher plate guide pin H⁸, the two being herein shown as in vertical alignment. 85

Mounted for movement on the carriage transversely of its path of reciprocation is a pusher plate structure generally indicated as J. It includes a handle member J¹ associated 90

with which are bearing sleeves J^2 J^3 about the 5 guide pins H^7 H^8 . The upper sleeve J^2 is shown as of considerably greater length than the lower sleeve J^3 in order to prevent binding upon the two pins. Extending from the handle portion J^1 across the top of the plate H^4 is the lateral extension J^4 to the outer end of which as at J^5 is pivoted the pusher plate proper J^6 . This pusher plate is provided 10 with a lower edge conforming generally to the face of the carriage plate H^4 but being provided for example at one corner with the roughened portion or teeth J^7 . If desired these teeth may extend across the whole lower 15 edge of the plate. The plate J^6 , being pivoted to the arm J^4 , is provided with a thumb piece or handle member J^8 whereby it may be lifted or rotated about its pivot. J^9 indicates a spring or any other suitable yielding 20 means whereby the plate is normally thrust into the lower limit position in which it is shown in Figure 1.

It is not allowed, normally, to engage the opposed surface of the plate H^4 , an abutment 25 J^{10} being provided on the arm J^4 to receive the corresponding abutting member J^{11} of the face plate. J^{12} indicates an adjustment whereby the adjustment of the pusher plate at its lowest position may be made. In order to 30 guide the pusher plate in its rotation to hold it, during such rotation, in the desired plane, I provide a guide J^{14} on the pusher plate which engages the rounded or reduced portion J^{15} of the arm J^4 by the slot J^{16} . This 35 is indicated as an example of a practical mechanism but applicant does not wish to be limited specifically to these various details.

Referring to Figure 4, which illustrates a modified form of my device, instead of pivoting 40 the plate J^6 to the end of the arm J^4 I interpose a plurality of links K K^1 whereby when the plate is rotated on said links the entire width of the plate moves in unison and the distance between the bottom of the 45 pusher plate and the opposed face of the carriage plate is uniform.

It will be realized that whereas I have described and shown a practical and operative device, nevertheless many changes might be 50 made in size, shape, number and disposition of parts without departing from the spirit of my invention. I therefore wish my description and drawings to be taken as in a broad sense illustrative and diagrammatic rather than as limiting me to my specific showing.

The use and operation of my invention are as follows:

I provide a form of slicing machine in 60 which a rotary motor driven knife is employed and in which the meat or other work is conveyed past the cutting edge or arc of the knife, upon a meat carriage which is guided along an inclined path by the tracks G and G^2 , the cutting stroke being up the 65 incline and the down or return excursion be-

ing down the incline. If desired the inclination of the tracks may be such as to cause the meat carriage to return to its initial position partly or entirely in response to gravity. In any case the inclination, in conjunction with the flat bottom plate H^4 of the carriage and the edge flange H^5 thereof, serves to hold the work at the junction of the members H^4 H^5 . Thus when slicing circular pieces of material, such as sausages or rolls of meat, the pitch or inclination of the meat carriage is sufficient to hold such circular pieces at the rear corner of the plate H^4 and in contact with the flange H^5 . Not only does this save time, but it insures a cleaner slice, since the flange H^5 , by abutting against the meat slice, prevents the tracking of the slice and the formation of fringes on the meat being sliced.

Furthermore, by the employment of the flat plate H^4 I largely increase the capacity of the device as compared to the prior devices in which a V-shaped trough is employed. In decrusting a loaf of bread, for example, or cutting the rind from a piece of bacon, the bread or the bacon can be laid on the flat surface H^4 and cut at one stroke or operation.

In employing the pusher plate I may use it as a pusher plate pure and simple, in which case the plate is in the position shown in full line in Figure 1.

On the other hand I may wish to use the plate as a clamp to hold down a small piece of meat. In such case I lift the plate or rotate it, for example by engaging the member J^8 with the thumb, and then permit the spring J^9 to thrust the plate downwardly against the work. In such case the teeth J^7 tend to clamp the work in position. In the form of Figure 1 the clamping action is exerted only by the inner portion of the pusher plate, since the pivot J^5 constrains the outer end to a close approach to the plate H^4 . In the variant form shown in Figure 4, the entire plate may be lifted as shown in dotted lines and its entire lower edge, or any point thereof, may exert the above described clamping action.

I claim:

1. In a slicing machine which includes a rotary knife and means for rotating it and a gauge plate adjacent said knife and a carriage movable across said gauge plate and knife, a pusher plate for said carriage and means for guiding it transversely of the path of movement of the carriage, the pusher plate being in pivotal relation with the carriage for rotation about an axis generally parallel with the path of movement of the plate, and means for normally holding said pusher plate in position with its lower edge closely adjacent the opposed top of the carriage, and adjusting means for limiting the movement of the pusher plate toward the carriage in response to said holding means.

2. In a slicing machine which includes a

- rotary knife and means for rotating it and a gauge plate adjacent said knife and a carriage movable across said gauge plate and knife, a pusher plate for said carriage and means for guiding it transversely of the path of movement of the carriage, a supporting arm for said pusher plate, extending across the carriage, the pusher plate being in pivotal relation with said arm, an abutment on said arm and an abutment on said pivot plate, the abutments being positioned to maintain the lower edge of the pusher plate in close proximity to the opposed face of the carriage.
3. In a slicing machine which includes a rotary knife and means for rotating it and a gauge plate adjacent said knife and a carriage movable across said gauge plate and knife, a pusher plate for said carriage and means for guiding it transversely of the path of movement of the carriage, a supporting arm for said pusher plate, extending across the carriage, the pusher plate being in pivotal relation with said arm, an abutment on said arm and an abutment on said pivot plate, the abutments being positioned to maintain the lower edge of the pusher plate in close proximity to the opposed face of the carriage, and an adjusting member associated with said abutments.
- 30 4. In a slicing machine which includes a rotary knife and means for rotating it and a gauge plate adjacent said knife and a carriage movable across said gauge plate and knife, a pusher plate for said carriage and means for guiding it transversely of the path of movement of the carriage, a supporting arm for said pusher plate, extending across the carriage, the pusher plate being in pivoted relation with said arm, an abutment on said arm and an abutment on said pivot plate, the abutments being positioned to maintain the lower edge of the pusher plate in close proximity to the opposed face of the carriage, and yielding means for normally thrusting the pusher plate downwardly against the abutment on said arm.
5. In a slicing machine including a rotary knife and means for rotating it, a guard plate positioned forwardly of said knife, and a gauge plate, a carriage and means for guiding said carriage across said gauge plate and guard plate along a path generally parallel with guard and gauge plates, but inclined upwardly toward the cutting edge of the knife, said carriage including a bottom supporting member lying in a plane generally perpendicular to guard and gauge plate and inclined in general parallelism with the inclination of the path of said carriage and a lateral wall extending upwardly along the lower edge of said bottom supporting member, said lateral wall lying in a plane generally perpendicular to the plane of said guard and gauge plates, the upper edge of said supporting member opposite said wall being unobstructed and a pusher plate mounted on said carriage and means for guiding it for movement toward and away from the cutting plane of the knife along a path generally perpendicular to guard and gauge plates.
6. In a slicing machine including a rotary knife and means for rotating it, a guard plate positioned forwardly of said knife, and a gauge plate, a carriage and means for guiding said carriage across said gauge plate and guard plate along a path generally parallel with guard and gauge plates, but inclined upwardly toward the cutting edge of the knife, said carriage including a bottom supporting member lying in a plane generally perpendicular to guard and gauge plate and inclined in general parallelism with the inclination of the path of said carriage and a lateral wall extending upwardly along the lower edge of said bottom supporting member, said lateral wall lying in a plane generally perpendicular to the plane of said guard and gauge plates, the upper edge of said supporting member opposite said wall being unobstructed.
7. In a slicing machine including a rotary knife and means for rotating it, a guard plate positioned forwardly of said knife, and a gauge plate, a carriage and means for guiding said carriage across said gauge plate and guard plate along a path generally parallel with guard and gauge plates, but inclined upwardly toward the cutting edge of the knife, said carriage including a bottom supporting member lying in a plane generally perpendicular to guard and gauge plate and inclined in general parallelism with the inclination of the path of said carriage and a lateral wall extending upwardly along the lower edge of said bottom supporting member, said lateral wall lying in a plane generally perpendicular to the plane of said guard and gauge plates, the upper edge of said supporting member opposite said wall being unobstructed, and a pusher plate mounted on said carriage and means for guiding it for movement toward and away from the cutting plane of the knife along a path generally perpendicular to guard and gauge plates.
8. In a slicing machine which includes a rotary knife and means for rotating it, a gauge plate adjacent said knife, and a carriage movable across the faces of the gauge plate and knife, a pusher plate lying in a plane generally parallel with the plane of the gauge plate and movable on said carriage, toward and away from the cutting plane of the knife, a support for said pusher plate, and means for guiding it along a path trans-

verse to the path of movement of the carriage,
said support extending transversely across
the upper face of said carriage, means for
holding said support against rotation, the
5 pusher plate being pivoted to said support
to render the bottom edge of said plate ad-
justable toward and from the adjacent plane
of the carriage.

Signed at Indianapolis, county of Marion
10 and State of Indiana, this 6th day of June,
1928.

WILLIAM J. CAMPBELL.
